UNITED STATES PATENT OFFICE.

EDMUND H. STRIKER, OF TORONTO, ONTARIO, CANADA.

SHEET-METAL TOBACCO-CADDY.

SPECIFICATION forming part of Letters Patent No. 298,255, dated May 6, 1884.

Application filed January 15, 1884. (No model.)

To all whom it may concern:

Be it known that I, EDMUND HERBERT STRIKER, of the city of Toronto, in the county of York, in the Province of Ontario, Canada, 5 gentle man, have invented certain new and useful Improvements in Sheet-Metal Tobacco-Caddies, of which the following is a specification.

The object of the invention is to devise a 10 sheet-metal tobacco caddy or package retaining all the advantages of an ordinary wooden tobacco-caddy, while possessing the additional advantages arising from its material and peculiar construction; and it consists, essentially, 15 in providing a peculiarly-flanged metal cover arranged to grip lips formed on the outside of the mouth of the caddy, the said cover being preferably provided with a detachable block of wood, the whole being arranged substantially 20 as hereinafter explained.

I am aware that sheet-metal caddies have been used previous to my invention; and I am also familiar with a certain sheet-metal tobacco-caddy patented by George T. Tuckett, of 25 Hamilton, Ontario, on February 27, 1883, No. 272,921, in which a flanged cover is arranged in connection with lips formed around the edge of the mouth of the caddy. There are serious objections to the plan adopted by Mr. Tuckett 30 to secure the cover of his caddy in position, and as these objections are completely overcome by my invention I may as well explain Mr. Tuckett's construction and point out wherein the objections lay, in order that the object and 35 effect of my invention may be more readily understood. In Mr. Tuckett's caddy lips are formed on the inside edge of the mouth of the caddy. The edges of these lips project downwardly within the caddy, and are intended to 40 catch and hold in position upwardly-turned flanges formed on the cover when the said cover is placed in position, the joint between the two being completed by hammering over the lip the edges of the mouth of the caddy 45 onto the top of the cover, forming what is known as a "double-seam joint." V-shaped pieces are cut out of the corners of the mouth of the caddy and the corners of the cover, in order that each side may be flanged independent of the others.

Among the objections to Tuckett's tobacco-caddy may be mentioned, first, that the inwardly-projecting lip employed by him for forming the connection between the top of the caddy and its cover not only presents a downwardly-projecting edge calculated to injure the hands of the workman inserting the tobacco, but as it reduces the diameter of the mouth of the caddy, the caddy itself must be larger than the plugs of tobacco inserted into it, which causes the tobacco pressed into it to present what is known among the trade as a "stair-cased side," which seriously affects the appearance of the tobacco, and thereby its sale. It is also impossible in the Tuckett caddy to 55 pack the tobacco in bulk in a caddy fitting the exact form of the bulk. It is also impossible to open the caddy to take a sample, as when once opened, owing to the manner of forming the joint between the cover and the 60 caddy, the metal forming the lips and flanges will be destroyed when the joint once made is 65 first broken.

There are other objections to the Tuckett caddy not necessary to mention, as the foregoing will be sufficient to exhibit by comparison the superiority of my improved construction.

Figure 1 is a perspective view of my improved caddy, showing a portion of the caddy broken away and the lid partially opened. Fig. 2 is an elevation of my improved caddy, the top portion of it being broken away, exhibiting the cover in the act of clipping over the retaining-lips. Fig. 3 is a similar view of 85 the caddy and cover, showing the joint completed between the cover and the caddy. Fig. 4 is a perspective inside view of the cover. Fig. 5 is a vertical cross-section of a portion of the caddy, showing the block of wood placed onto 90 the foraminated bottom.

In the drawings like letters of reference indicate corresponding parts in each figure.

A is the body of the caddy constructed in any of the well-known ways, and provided 95 with a foraminous bottom, E, soldered or otherwise secured thereto, into which the tobacco B is forced by a hydraulic or other powerful press.

C is a block of wood made to fit the interior 100

of the caddy A, which block of wood is placed on top of the tobacco, between it and the cover, before the pressure is directed against the tobacco for forcing it into the caddy. As the 5 retaining-lips a project on the outside of the caddy A, the tobacco B fits exactly the interior of the caddy, and in packing it the operator finds a perfectly smooth surface on the inside of the caddy instead of a rough cutting- 10 edge which would interfere with the packing of the tobacco, were the lips formed on the inside, as in the Tuckett package.

D is a sheet-metal cover, having the flanges b formed around its four sides, an upwardly- 15 turned lip being formed on the lower edge of each flange, as shown in Fig. 2, in which figure the lip is represented in the act of passing down over the retaining-lip a. As soon as the 20 edges of the two lips pass each other and the pressure is removed, the expansion of the tobacco within the package will naturally force the cover D upwardly. The upwardly-turned lips on the flanges b will naturally spring under the retaining-lips a, and when the joint 25 thus formed is hammered it is complete, as shown in Fig. 3.

The importance of the wooden block C will be here appreciated, for in hammering the joint it presents a solid backing against which 30 the hammering may be effectually directed, thus enabling a perfect joint to be made without in any way injuring the surface or edge of the tobacco within the package. This block also fills up the open space which would otherwise be left at each corner of the cover, owing 35 to the necessity of cutting out of each corner a piece of metal to enable the proper flanging of the cover.

I have referred to the block as being detachable; but it will of course be understood that 40 the cover D may be tacked to the block when desired.

As a metal package will not absorb the moisture from the tobacco as a wooden package will, the employment of a metal package, 45 should the tobacco be unusually damp, may cause the tobacco B to mold. I therefore think it will be advisable to perforate the cover D, so as to expose the wooden block C. This block, as in the case of a wooden package, will 50 absorb the moisture, and being thus exposed to the atmosphere throws off the moisture thus absorbed. If desired to do so, I sometimes insert a wooden block at the bottom of the package, and in this case the bottom would be perforated in the same manner as the top. 55

As my invention is directed toward the improvement of packages for containing tobacco, I have through the specification referred to it merely as a tobacco-caddy; but it will of course be understood that a package or case for any use might be advantageously made in accordance with my invention.

What I claim as my invention is—

1. A sheet-metal caddy or case, A, provided 65 with retaining-lips a, formed outwardly at its mouth, in combination with the sheet-metal cover D, having flanges b, with upwardly-turned lips on the lower edge of each flange, substantially as and for the purpose specified. 70

2. A sheet-metal cover, D, having flanges b, with upwardly-turned lips on the lower edge of each flange, a wooden block, C, applied as specified, in combination with a caddy, or case A, having retaining-lips a, formed outwardly 75 at its mouth, substantially as and for the purpose specified.

Toronto, January 4, 1884.

E. H. STRIKER.

In presence of—

CHARLES C. BALDWIN,
F. BARNARD FETHERSTONHAUGH.
